ASSIST HANDLE FOR AUTOMOBILE ROOFS

Witold Szenher, 5642 Baltimore Ave., Philadelphia, Pa.

Filed Aug. 18, 1960, Ser. No. 61,816

Term of patent 14 years

(Cl. D10—8)

FIG. 2

FIG. 3

FIG. 5

FIG. 1 is a front elevational view of an assist handle for automobile roofs showing my new design;

FIG. 2 is a rear elevational view thereof;

FIG. 3 is a bottom plan view thereof;

FIG. 4 is an end elevational view looking from the right of FIG. 1; and

FIG. 5 is a sectional view through the longitudinal bar of FIG. 1 showing the configuration thereof.

I claim:

The ornamental design for an assist handle for automobile roofs, substantially as shown.
